TUMBLING MILL

James R. Allan, Oak Park, and Frank H. Amos,
Chicago, Ill., assignors to International Harvester Company, a corporation of New Jersey

Application April 5, 1934, Serial No. 719,114

9 Claims. (Cl. 51—164)

This invention relates to tumbling mills for smoothing and cleaning rough castings and the like. Castings taken from sand molds are usually placed in tumbling mills along with irregular shaped elements to facilitate the tumbling operation for removing sand and metallic fins from the castings. The tumbling mills are often formed as a barrel-like drum or casing, or of polygonal cross section journaled for rotation. 5 A door is provided for insertion of the castings, which is then securely closed and the casing is rotated until the desired tumbling action has been accomplished.

In a tumbling mill, the sand particles being removed from the castings are ground to a dust-like material which escapes from the mill and fills the air of the plant around the mill. Such dust formation is very injurious to the workers in a foundry and constitutes at the present time one of the greatest industrial hazards. To remove the dust from the mill it has been past practice to perforate the ends of the mill and pass a blast of air through the tumbling drum during the tumbling operation. This method has been only partially successful, because the load of castings fills the cross section of the mill and thereby offers a substantial reduction in mill cross sectional area available for the proper volume and velocity of air to carry away the dust and dirt created by the tumbling action. 30 Also, as a large percentage of the sand when removed from the castings is too heavy to be carried by the available air blast through the center of the mill, it falls by gravity to the lower edge and keeps sliding around with the rotation of the drum until it is ground into powder form and leaks through the mill joints. As the castings tend to mat together, in a sense, in the lower half of the casing, the air blast does not penetrate these castings with sufficient velocity to pick up the dust particles.

The principal object of the present invention is to provide an improved ventilating means for a tumbling mill. A more specific object is to devise a ventilating system which can be readily applied to a conventional mill of the type now in use, as well as to a new mill. Another object is to shorten up the tumbling operation by getting the sand and dirt out of the mill at the location 50 at which it tends to accumulate in the present style of mills. Another object is to improve the mill operation, particularly for small castings, by using smooth, imperforate end walls, thereby reducing breakage. These and other objects, 55 which will be apparent in the detailed descrip-

tion to follow, are attained by a construction such as illustrated in the drawings, in which:

Figure 1 is a vertical cross section of a tumbling mill incorporating the improved ventilation system;

Figure 2 is a section taken on the line 2—2 of Figure 1;

Figure 3 is a vertical cross section of a contemplated mill, showing a modified form of construction; and,

Figure 4 is a section taken on the line 4—4 of Figure 3.

As illustrated, a long cylindrical drum 10, which may be formed of sheet steel welded or riveted together, or by any other means, is provided with a removable door 11, through which castings may be inserted and removed. At diametrically opposite locations along the wall of the drum 10, a series of perforations 12 is formed. At each end of the cylindrical drum, circular head members 13 are also provided in a central area with a series of perforations 14. A head retaining member 15 is secured at one end of the casing to the cylindrical wall of the drum 10, forming an abutment for the end member 13 at that end. The central portion of the member 15 is spaced axially away from the perforated portion of the member 13 to form an air inlet chamber 16. A series of circumferentially arranged openings 17 form air inlets to the chamber 16. At its center portion the member 15 has a projecting portion 18, in which a bearing sleeve 19 is mounted. The bearing sleeve forms a raceway for roller bearings 20. The inner raceway for said bearings is provided by the projecting end of a short shaft 21 rigidly secured to a supporting standard 22.

A large ring gear 23 secured to the end member 15 provides means for rotating the drum by means of a driving gear 24 mounted on a shaft 25, to which power is supplied from any suitable source.

At the other end of the drum 10, a head retaining member 26 is secured by a peripheral flange to the outer end of the drum forming an abutment for the member 13 at that end. The central portion of the member 26 is formed with an axially directed extension 27, which forms an outlet chamber 28 for the perforations in the member 13. Beyond the extension 27, an additional, axially directed extension 29, somewhat smaller in diameter, forms an extension of the chamber 28. Axially beyond the extension 29, an axially directed extension 30 forms a sleeve in which a bearing sleeve 31 is mounted. Said sleeve forms the outer race for a roller bearing of the

same structure and supported in the same manner as at the other end of the drum, and identified by the same numerals.

A partition 32 closes off the chamber 28. In addition to the air inlet openings 14 to said chamber, two diametrically positioned openings 33 are formed in the periphery of the extension 27. Said openings are in radial alignment with the rows of openings 12 in the drum. At the sides of the openings 33, spaced, radially and axially directed walls 34 extend outwardly to the flanged portion of the member 26, the edges of said walls lying in a plane passing through the end of the drum 10.

Conduits 35 formed by channel-shaped members 36 extending axially of the drum over the perforations 12 connect with radial conduits 37 formed by radial extensions of the members 36, which radial portion is designated by a numeral 38. At the left end of the drum, as illustrated, the channel-shaped members 36 abut the peripheral portion of the ring gear 23, the opening 39 being formed for inlets to the conduit formed by said member. The construction at each side of the casing is exactly the same, there being two diametrically positioned conduits 35 and corresponding radial conduits 37. The side walls of the channel-shaped members 36 abut the walls 39 and are secured thereto and also to the peripheral wall of the extension 27, to form dust tight seals. These channel-shaped members may be secured by arc-welding or by any other suitable method by which a dust tight joint may be obtained.

A casing 40 is mounted around the extension 30 supported by the standard 22 at that end. Said casing forms a dust and air receiving casing and is connected by a conduit 41 with suction producing means. The outer wall of said conduit is fitted around the extension 30 by a suitable seal to prevent the escape of dust or inlet of air. The other side of the casing is fitted around the extension 29 by a seal 42, to prevent the escape of dust or the inlet of air. The chamber 28 communicates with the casing 40 by openings 43 formed in the member 26 between the extension 29 and the extension 30 of reduced diameter. A series of fins 44 are shown extending inwardly from the periphery of the extension 27. Said fins tend to distribute the air blast and prevent the accumulation of foreign material in the chamber 28.

In the operation of a tumbling mill as above described, the articles and the elements used in the tumbling operation are placed in the mill and it is rotated at the desired speed. Suction produced by a suitable source draws air through the conduits 35 and through the openings 17. A current of air is produced through the center of the drum, passing in through the openings 14 at the left end, as illustrated, and out through the openings 14 at the right end. In addition to this current of air, air flows through the conduits 35 and 37 into the air inlet casing. As the particles of sand and other foreign particles, such as metallic dust, fall by gravity to the outer edge of the drum during rotation, this material sifts through the openings 12 in metered amounts during each revolution of the drum and is picked up by the relatively high velocity air blast in the conduits 35. As there is no appreciable restriction to air flow in said conduits, the dust is carried away in a manner much improved over the previous type of mill, in which air passed directly through the mass of castings within the tumbling mill.

The modification shown in Figures 3 and 4 is somewhat different in that the air is supplied by a duct through the supporting trunnion, whereby it may be taken in from an outside unheated source. The volume of air used in an installation of this type is such that to take in air from the vicinity of the drum, heating of the building in which the machine is installed may be seriously interfered with. The modification of Figures 3 and 4 also differs in entirely eliminating axial flow of air through the drum and thereby making possible the provision of smooth end walls which do not engage and interfere with the free tumbling of the castings.

In Figures 3 and 4, the cylindrical drum 45 is formed with a circular head 46 at each end, carrying integrally therewith a hollow trunnion 47. Said trunnions are rotatably supported by standards 48. A gear 49 at one end of the drum provides means for rotation by the application of power from a driving gear 50. At each end of the drum 45, a smooth circular end plate 51 is positioned in spaced relation to the head 46. Spaced radially extending walls 52 form a pair of automatically aligned air passages 53. Said passages communicate with the hollow trunnions 47. Cone-shaped projections 54 from the end walls are provided to form a passage of substantially uniform velocity, the area of the passage 55 in the hollow trunnion being substantially the same as the sum of the cross sectional areas of the two passages 53. In alignment with the outer ends of the passages 53 and communicating therewith, channels 56 are arranged along the drum and secured thereto by welding or by other suitable means. Said channels are substantially the same in cross sectional area as the passages 53, whereby a substantially uniform velocity of air prevails throughout the entire system from the inlet end to the discharge end. The air passages 57 formed by the channels 56 communicate with the interior of the drum by a plurality of small orifices 58. These orifices provide means as above set forth in describing the operation of the other form shown in Figures 1 and 2 to receive sand and metallic particles loosened from the castings. As the drum rotates, a certain amount of sand collected is delivered to each passage 57 by gravity as the channel 56 passes the bottom position. By a construction of this type a high uniform air velocity is prevalent at all times in the ventilating system, whereby the material dropped into the system is completely carried away without any tendency to accumulate at various points. Moreover, as there is no area restricted or of large cross section, there is no reduction of velocity at any time or at any location.

As previously stated, the modification of Figures 3 and 4 differs from the form of Figures 1 and 2 in not having perforations in the end walls 51. In practice, it has been found that the changes in air velocity brought about by either lowering the cross sectional area or by increasing the restriction when end openings are utilized is a serious problem. Also it has been found that a smooth end wall is preferable to obtain satisfactory tumbling operations, as even small perforations sometimes prevent free tumbling action adjacent the end walls.

It is to be understood that applicants have shown their improved tumbling mill as a particular type to be built up originally with the ventilation system incorporated. It is to be un-

derstood, however, that the ventilation system of the invention may be incorporated in various types of mills and may be added to conventional mills now in use. All such modifications and uses as are covered by the following claims are considered as part of the present invention.

What is claimed is:

1. A ventilated tumbling mill comprising a supporting structure, a tumbling drum rotatably mounted on said structure, a ventilating conduit extending along said drum and carried thereby, said conduit being open for the inlet of air exteriorly of the drum at one end and being separated from the interior of the drum by a perforated wall, and means for withdrawing air and dust from the other end of the conduit.

2. A ventilated tumbling mill comprising a supporting structure, a tumbling drum rotatably mounted on said structure, a conduit mounted on said drum, openings formed in the conduit and communicating with the interior of the drum, means for admitting air exteriorly of the drum to one end of said conduit, and means for withdrawing dust and air from the other end of the conduit.

3. A ventilated tumbling mill comprising a supporting structure, a tumbling drum rotatably mounted on said structure, means for driving said drum, a plurality of ventilating conduits extending lengthwise of the drum, means for admitting air to said conduits at one end of the drum, and means for removing air and dust from the conduits at the other end of the drum, said conduits being in communication with the interior of the drum by a plurality of openings formed along the conduits and extending through the tumbling drum.

4. A ventilated tumbling mill comprising a supporting structure, a tumbling drum rotatably mounted on said structure, a plurality of ventilating conduits extending lengthwise of the drum and carried thereby, said conduits being separated from the interior of the drum by perforated walls, means for admitting air to the conduits at one end of the drum, and means for removing air and dust from the conduits at the other end.

5. A ventilated tumbling mill comprising a supporting structure, a cylindrical tumbling drum rotatably mounted on a horizontal axis on said structure, means for driving said drum, a plurality of ventilating conduits extending lengthwise of the drum, means for admitting air to said conduits at one end of the drum, a plurality of openings formed in the conduits providing communication between the interior of the drum and the conduits, means opposite the inlet ends of said conduits forming a common discharge chamber, a discharging conduit mounted on the sup-

porting structure, and means for connecting said conduit with the discharge chamber.

6. A ventilated tumbling mill comprising a supporting structure, a cylindrical tumbling drum rotatably mounted on a horizontal axis on said structure, means for driving said drum, a plurality of channel-shaped members extending lengthwise of the drum and secured to the outer surface thereof, perforations being formed in the wall sections of the drum covered by said members, means for admitting air at one end of the drum to the conduits formed by said members and the enclosed perforated portions of the drum, and means for removing air and dust from the conduits at the other end of the drum.

7. A ventilated tumbling mill comprising a supporting structure, a cylindrical tumbling drum rotatably mounted on a horizontal axis on said structure, means for driving said drum, a plurality of channel-shaped members extending lengthwise of the drum and secured to the outer surface thereof, perforations being formed in the wall sections of the drum covered by said members, means for admitting air at one end of the drum to the conduits formed by said members and the enclosed perforated portions of the drum, and means for removing air and dust from the conduits at the other end of the drum, said means including a stationary casing mounted on the supporting structure, a common discharge means carried by the drum and communicating with said casing, and means for connecting the ventilating conduits with said discharge chamber.

8. In a ventilated tumbling mill having a rotatable tumbling drum and in combination therewith, a ventilating and dust removing conduit extending along said drum and carried thereby, a perforated wall between the conduit and the drum forming communication therebetween, means for freely admitting air to one end of the conduit, and means for withdrawing air from the other end of the conduit effective to produce an air stream of substantial velocity through the conduit.

9. In a ventilating tumbling mill having a rotatable tumbling drum and in combination therewith, a ventilating conduit extending along said drum and carried thereby, a perforated wall between the conduit and the drum forming a restricted communication therebetween whereby a metered amount of dust and other material may be delivered from the drum to the conduit with a minimum amount of air, means for freely admitting air to one end of the conduit, and means for withdrawing air from the other end of the conduit for producing an air stream of a substantial velocity through the conduit effective to pick up and carry away material delivered thereto through the perforated wall.

JAMES R. ALLAN.
